R. F. HALL

MACHINE FOR THE MANUFACTURE OF GLASS ARTICLES

Filed July 27, 1920

Inventor:
R. H. Hall
By his Attorney,

Bruden Wight

UNITED STATES PATENT OFFICE.

ROBERT FREDERICK HALL, OF MOSELEY, NEAR BIRMINGHAM, ENGLAND.

MACHINE FOR THE MANUFACTURE OF GLASS ARTICLES.

Application filed July 27, 1920. Serial No. 399,433.

To all whom it may concern:

Be it known that I, ROBERT FREDERICK HALL, a subject of the King of Great Britain and Ireland, residing at Moseley, near 5 Birmingham, in the county of Warwick, England, have invented certain new and useful Improvements in Machines for the Manufacture of Glass Articles (for which I have filed an application in Great Britain, No. 8769, filed Jan. 21, 1918), of which the following is a specification.

This invention relates to rotary machines for the manufacture of glass articles, and refers to that type of such machines in which the molten glass, from which the articles are to be formed, is drawn by means of suction into a parison or other mold, the said mold being open at the bottom and being lowered to the surface of the molten glass, to enable the glass to be drawn into the interior thereof, after which the mold is raised and the parison therein contained is enclosed in a finishing mold and carried through the various operations for the production of the finished article.

It has already been proposed to mount the finishing or blowing molds in connection with a main rotatable framework so that they are adapted to swing upwards, and to raise them at appropriate times by means of rack and pinion gearing or by means of a roller attached beneath the swinging framework and running upon a suitable camway.

My present invention has for one of its principal objects to provide improved means for carrying, raising and lowering the finishing molds and associated parts.

A further object of the invention is to provide improved means for opening and closing the mold, so that such opening and closing may be readily effected irrespective of the position or movement of the swinging frames or the like carrying the molds.

Other objects of the invention will also be referred to in the specification as regards minor constructional details and arrangements.

In the general way of carrying out my invention, each finishing mold is carried by a pivoted frame or member, constituting a lever of the first order, adapted to swing about a horizontal axis, is counterbalanced and is adapted to be raised and lowered at

appropriate times by means of a cam or an 55 electric solenoid or by fluid pressure or by a combination of any or all of these means.

The opening and closing of the halves of the mold are operated by a lever or levers or the like independently of the movements 60 or position of the frame or member carrying the molds.

This opening and closing may be effected by toggle mechanism operated by a lever pivoted to the swinging frame, the said 65 lever being operated through suitable mechanism, from a cam in connection with the fixed framework of the machine.

I prefer to mount the mechanism carrying the finishing mold and its associated 70 parts in an elongated loop or its equivalent, adapted to be easily placed in position so as to form an integral portion of the main framework, and easily removed from such framework to facilitate the building and repair of the machine.

In order that my invention may be more clearly understood I will now proceed to describe the same with reference to the accompanying drawing which shows more or 75 less diagrammatically a part sectional elevation of the mechanism for operating and controlling the finishing mold of one unit of a bottle making machine of the general type more particularly described in my co-pending application No. 399,427, filed July 27, 1920.

The numerals of reference in the following description correspond as far as possible with those used in connection with the drawings accompanying my said co-pending application.

1 indicates one of the supporting wheels, adapted to run upon rails 2, in the neighborhood of the furnace, in the ordinary 80 manner.

The wheels support the main lower framework of the machine which is composed of longitudinally disposed girders 7 connected by transverse girders 8.

The girder framework 7, 8 carries a ring 11, which in turn carries a channeled ring 12, forming the lower member of a ball bearing. 14 is another ring forming the upper member of the ball bearing, and to this 105 latter ring is attached an internally toothed annulus 15.

Suitably supported upon the lower girder

framework 7, 8 is a vertical column 16, carrying the principal non-rotatable parts of the machine.

These parts as far as they are shown in the present drawing comprise a large cam 17 carried by brackets 18 connected in turn to vertical struts 19, carried by brackets 20 from the column 16. 24 is another cam carried by suitable brackets 25 on the fixed framework of the machine.

Bolted between a rotatable member at the top of the machine and the annulus 15 is a column or framework 96 hereinafter called "the bifurcated column," a column of this description being provided for each bottle making unit.

Each column is formed from castings of H section at the lower part and solid up to the height of the trunnions 31, from which position to the top they are hollow, so that air may be passed down from the air reservoir to the top of the machine to the trunnions 31.

The upper part of the bifurcated column may carry the parison mold and its associated mechanisms which need not be described in detail, in the present specification, as they form the subject of a co-pending application.

As already explained, each of the bifurcated columns is formed at 31 with bearings in which work the trunnions of the lever or frame carrying the finishing mold and its associated parts.

This consists of a casting 300 formed with a suitable passage for air in connection with the hollow passages in the sides of the bifurcated column through the trunnions and bearings 31.

The casting 300 with the extension arm 300^a on the other side of the trunnion 31 constitutes a lever of the first order.

301 is a counterbalance weight, which is preferably somewhat heavier than the finishing mold and associated parts, so that the said mold tends normally to remain in the raised position.

The weight 301 is adapted to slide vertically upon a guide 302 connected by means of a horizontal stay 303 to the bifurcated column above the trunnions 31.

At the lower end the vertical guide 302 is of T shape and is connected by two horizontal stays 304 to the base 305 of the bifurcated column 96.

It will thus be seen that the weight 301 can slide vertically upon the guide 302, which passes therethrough.

The arm 300^a is bifurcated, one of the arms of the fork coming on each side of the weight. Each arm is provided with a roller 306, and each of these rollers is adapted to work in a horizontal slot 307 on the outside of the weight 301 so that as the weight rises and falls, it raises and lowers the frame 300 by turning it about its fulcrum 31.

The raising and lowering of the weight

is effected from the cam 24 by means of the rollers 117 attached to the lower portion of the weight 301.

It will be observed that the drawing shows one half 52 of the parison mold (carried by the arm 49 from the pivot 53) behind one half M of the finishing mold.

The opening and closing of the finishing mold is effected in the following manner.

Each of the arms carrying one half M of the mold is extended backwards beyond the bearing and the ends of the arms are connected to linking rods which are in turn connected to a slide block 122, a helical compression spring surrounding each of the rods.

The block 122 is connected to an S shaped lever 123, pivoted at 124 to the swinging framework 300. The S shaped lever 123 is connected at 125 to a link 126, which is pivoted at 127 to one arm of a bell crank lever pivotally mounted at 128^a in a recess within the weight 301.

The other arm of this bell crank lever is pivoted at 308 to a vertical rod 309 which is operated from rollers 310 in connection with the cam 17.

It will be seen that the cam 17 may be so proportioned and arranged that the opening and closing of the finishing mold can be effected to suit requirements independently of the position of the mold. In practice it is usual to open the finishing mold only when in the lowered position, after the glass has had the maximum amount of time for cooling and when the bottle or the like is ready to be discharged from the mold.

The method of mounting and operating the finishing mold hereinbefore described possesses important advantages.

Where the rise of the mold is brought about solely by means of a cam, as is usually the case with rotary machines for the manufacture of bottles or the like, there is considerable friction and a large amount of work has to be expended in order to effect the raising, and in any case the use of steep cams to effect a raising operation is to be deprecated.

The counterbalance weight which it is to be remembered tends normally to keep the blowing mold pressed securely in the correct position relatively to the neck mold causes very little work to be expended in the operation of the raising of the mold, since the cam rollers in connection with the weight simply run down a steep slope on the cam. On the other hand, the slope which raises the weight and depresses the mold may be of comparatively moderate gradient and if the amount of weight on each side of the fulcrum is nearly equal, the operation of lowering the mold by raising the weight also causes very little work to be expended.

In some cases the raising and lowering of

the finishing mold may be effected by means of an electric solenoid or by means of a fluid pressure motor, working alone or in combination with suitable cams.

5 Examples of raising and lowering the counterbalance weight of the finishing molds by means of an electric solenoid or by a fluid pressure motor being given in my co-pending application Ser. No. 399,430, filed July 10 27, 1920, it is not thought necessary to illustrate these methods in detail in connection with the present specification.

It is to be pointed out that in the preferred construction the lever carrying the finishing mold is mounted in an elongated loop or its equivalent more fully described in the specification of my said co-pending application, which can be easily removed from the rotatable framework of the machine by unbolting it from the rotatable ring at the bottom and from the arm or the like at the top; or in some cases both the arm and the elongated loop or its equivalent may be detached as a whole. It is also preferable 20 to mount the parison mold and its associated parts in the same elongated loop at a higher level, so that the parison and finishing molds of any unit can be removed as a whole and the unit can be quickly replaced by a fresh 25 one in case of accidents without stopping the machine for any considerable time. As an alternative the unit may be removed altogether and the machine can be worked without the said unit.

30 35 It will be understood that the particular details of construction may be varied without departing from the principle of my invention.

What I claim as my invention and desire to secure by Letters Patent is:—

1. A finishing mold mechanism for machines for forming glass articles comprising a supporting member, a swinging mold carrying frame pivotally supported between 45 its ends on the supporting member, a finishing mold on the swinging frame member at one side of the pivot, and means connected to the frame member at the other side of the pivot for swinging the frame 50 member.

2. A finishing mold mechanism for machines for forming glass articles comprising a supporting member, a swinging mold carrying frame pivotally supported between 55 its ends on the supporting member, a finishing mold on the mold carrying frame at one side of the pivot, a counterbalance on the frame at the other side of the pivot, and means for effecting a swinging movement 60 of the mold carrying frame member.

3. A finishing mold mechanism for machines for forming glass articles comprising a supporting member, a swinging mold carrying frame pivotally supported between 65 its ends on the supporting member, a finish-

ing mold carried on the swinging mold supporting frame at one side of the pivot, a vertically movable weight having a sliding and pivoted connection with the mold carrying frame at the other side of the pivot, a 70 guide on which the weight is vertically movable, and means for effecting a vertical movement of the weight.

4. In a machine for the manufacture of glass articles the combination of a rotatable 75 framework, a lever of the first order, pivoted to the said framework, a finishing mold carried by the outer arm of the said lever, a counterbalance weight in connection with the inner arm of the said lever, and means 80 for moving said weight at appropriate times, for the purposes set forth.

5. In a rotary machine for the manufacture of glass articles, the combination of a rotatable framework, a bent lever of the 85 first order pivoted to the said framework, a sectional finishing mold carried by the outer end of the said lever, a counterbalance weight in connection with the inner arm of the said lever, and means for moving said 90 weight at appropriate times, for the purposes set forth.

6. In a machine for the manufacture of glass articles, the combination of a fixed base, a framework rotatable on the said base, 95 a bent lever of the first order pivoted to the rotatable framework, a sectional finishing mold, the sections of which are carried by arms pivoted to the outer arm of the said lever, a counterbalance weight in connection with the inner arm of the said lever, means for moving said weight, and means for operating the arms carrying the sections of the mold, for opening and closing the same, substantially as described. 100

7. In a machine for the manufacture of glass articles, the combination of a fixed base, a framework rotatable upon the said base, a bent lever of the first order pivoted to the rotatable framework, a finishing mold 110 carried by the outer arm of the said lever, a weight slidable in guides in the framework, means in connection with the weight for engaging the inner end of the said lever, and means for raising and lowering the 115 weight, for the purposes set forth.

8. A finishing mold mechanism for machines for forming glass articles including a stationary frame, a rotatable frame mounted thereon, a cam track on the stationary 120 frame, a swinging finishing mold carrying member pivotally supported between its ends in a part of the rotary frame, a finishing mold on the pivotally supported mold carrying member at one side of the pivot, a counter-balance having a sliding and pivoted connection with said swinging mold carrying member at the other side of the pivot, means 125 for moving the counterbalance vertically up or down to swing the pivoted mold carry- 130

ing frame through an arc, guides for the counterbalance whereby it is held against lateral movement, and means including an arrangement of links pivotally carried by the counterbalance for effecting the operation of the finishing mold, said means also including a cam adapted to engage in said cam track, the arrangement being such that the mold can be operated independently of the position of the counterbalance.

9. In a machine for the manufacture of glass articles, the combination of a fixed base, a framework rotatable on the said base, a bent lever of the first order pivoted to the rotatable framework, a finishing mold carried by the outer arm of the said lever, a weight slidable in vertical guides in the said framework, horizontal slots in the weight engaging rollers at the inner end of the lever, a cam in connection with the fixed base, and a cam follower to said cam, such follower being connected to the weight, for the purposes set forth.

10. In a machine for the manufacture of glass articles, the combination of a fixed base, a framework rotatable on the said base, a bent lever of the first order pivoted to the rotatable framework, a sectional finishing mold, the sections of which are carried by arms pivoted to the outer arm of the lever, a counterbalance weight slidable in vertical guides in the framework, a slidable means of engagement between the said weight and the inner arm of the lever, a cam in connection with the fixed base, a follower to said cam, such follower being connected to the weight, toggle mechanism in connection with the arms of the finishing mold, another fixed cam upon the fixed base, a follower to said cam, such follower being connected to the toggle mechanism operating the arms of the finishing mold, substantially as described.

In testimony whereof, I have hereunto subscribed my name.

ROBERT FREDERICK HALL.
